UNITED STATES PATENT OFFICE.

FERRUCCIO F. CONTOLINI, OF UNION CITY, NEW JERSEY.

TAMBOURINE BALL GAME.

Application filed February 12, 1927. Serial No. 167,674.

- This invention relates to ball games, and more particularly refers to devices to be used in playing various ball games, and its primary object is to provide a tambourine of a novel and improved construction, affording a very firm grip and enabling thereby the player to vigorously strike and return a ball which has been batted into his territory by the opposing player.
- Another object of the invention is to provide a tambourine of an improved type, provided with a special reinforcement for the wrist of the player, insuring a free movement of the wrist, and at the same time preventing undue tilting of the tambourine under the effect of the impact of the ball.
- A further object is to provide a tambourine of an improved design adapted to be gripped by the hand of the player at a point of its periphery, the construction of which is slightly unbalanced, being somewhat heavier at the gripping point so as to produce an excess of weight at said point, tending to counterbalance the effect of the weight of the tambourine beyond and overhanging from said point.
- Other objects and advantages of the present invention will more fully appear as the description proceeds and will be set forth and claimed in the appended claims.
- The ball game for which the type of tambourine forming one of the objects of the present invention is more particularly designed is usually played in a field about 155 yards long, by about 33 yards wide, using fairly solid rubber balls weighing about 2 ounces. Mid-way between the ends of the field a visible dividing line is marked running across the field called the middle foul line. This line divides the batting squad from the remitting squad.
- Each of the two teams consists of five men, comprising the batter, left halfback, right halfback, left forward and right forward.
- The batter at the remitting side is called the remitter, and each of the opposing squads must not encroach on the opponents' territory.
- When the game is started, the batter stands on his goal line midway of the field in a designated space large enough to allow him to take six or eight steps to bat the ball in play. The ball must reach the opponents' ter-
- ritory before touching the ground, the object of the players being to bat the ball beyond their opponents' goal line.
- After the first toss has been made and the ball has soared to the remitters' territory, they must bat it in return towards the batting side either while the ball is in the air, or after the first bound only. Their object in so doing is also to bat the ball beyond the goal line of the opponents' territory.
- Various other rules go to complete the game, but the point which it is important to note is that in view of the length of the field and the weight of the ball, the devices used to bat or to return the ball must of necessity be able to stand a tremendous impact.
- For the same reasons the game is a strenuous one also for the players who must be able to have full control of their batting strokes, and who must be able to apply all their energy in batting or returning the ball. It is, therefore, a matter of surpassing importance for the player to be provided with batting devices affording a very firm grip, having means for counterbalancing the effects of the weight of their overhanging portion. Furthermore, the batting devices must be strongly built and yet must be of a relatively light weight.
- Tambourines consisting of a piece of rawhide tightly stretched over a hollow frame have been heretofore used in playing this kind of game, the tambourines being circular in shape. The rawhide covering has a very high resistance, and by being tightly drawn about its frame it becomes highly resilient, enabling the player to cause the ball to rebound to a great distance; but the types of tambourines heretofore in use did not afford a very firm grip so that frequently the impact of the ball at the receiving end would cause the player to lose the grip and to make a faulty delivery of his stroke. This action of the ball was furthermore assisted by the weight of the overhanging portion of the tambourine which tended to increase the strain exerted upon the hand of the player.
- The tambourine forming the object of the present invention represents an improvement over the previous art, especially in view of the simple and positive means introduced in its construction for insuring a firm grip of the tambourine by the player. This fea-

ture is extremely important, as stated, in a game such as this requiring a great deal of skill, where the attention of the player must not be distracted from the main object of squarely catching and returning the ball coming from a great distance and great height towards him.

The preferred embodiments of my invention are illustrated in the drawings where—
10 Fig. 1, is a rear view in elevation of a tambourine embodying my invention;

Fig. 2, is a plan view of the same;

Fig. 3, is a cross sectional view in elevation of the same through line 3—3 of Fig. 2;

15 Fig. 4, is a fragmentary view in elevation in an enlarged scale of the gripping end of the tambourine;

Fig. 5, is a cross sectional view in elevation of a tambourine of a slightly different 20 construction;

Fig. 6, is a view in perspective of a tambourine having an elongated shape, adapted for use at the start of the game, also embodying my invention;

25 Fig. 7, is an end view in elevation of the same, partly broken away;

Fig. 8, is a view in perspective of said tambourine illustrating its manner of outwardly projecting from the hand of the player;

30 Fig. 9, is a rear view in elevation of a tambourine similar to that shown in Figs. 1-3, illustrating a different construction of gripping of wrist strap.

Referring to said drawings, Figs. 1-4, illustrating a tambourine of the ordinary round type, in which (10) designates a round frame which is generally formed of two rings (11)—(12) inserted one within the other, made of relatively thin, flexible wood in strip form. Over said frame is tightly stretched a piece of rawhide having its edge bent all around the frame, as shown at (13), and forming a resilient top (14) for the tambourine. The rawhide is secured to the frame along its rim portion in any suitable manner, for instance, by means of nails or screws (15). The bent portion of the rawhide is, furthermore, surrounded and clamped by another ring (16), also made of a relatively thin strip of wood or other suitable material.

In order to enable the player to firmly grip the tambourine at a point along its circumference, the inner surface of the frame is provided at said point with a segmental inward projection (17) which is flush with the bottom edge of the frame and which does not extend the entire depth of the frame. In practice the frame is about $1\frac{1}{2}$ inches deep, and the thickness of the segmental projection is about half as much, leaving a clearance space (18) between the top of the projection and the lower surface of the rawhide.

By virtue of this construction, the player is enabled to grip the tambourine by bending his fingers upwardly and then inwardly

about the segmental projection and within this clearance space (18), as clearly illustrated in Fig. 4. This detail of construction of itself enables the player to counteract to a certain extent the impact of the ball striking 70 the tambourine, due to the tight grip that he can exert on the L sectioned resulting gripping structure, and also owing to the pressure that he can exert with the tips of his fingers 75 against the upper surface of the segmental projection and against the inner surface of the frame. The gripping action is furthermore assisted, and a smoother surface provided if both the frame and the segmental projection are covered by a piece of leather 80 such as (19), extending all around the frame and the segmental projection at the gripping end. Said leather may be set and retained in position by means of nails and screws such as (20), and is furthermore secured at the two ends by metal strips such as (21), bent in U fashion and extending upwardly from the bottom of the frame, close to the inner and outer surface thereof.

The positive grip feature described is completed by another important addition in the nature of a strap (22) attached at its two ends (23), (24) to the outer surface of the frame and in correspondence of the two ends 90 of the segmental projection. Said strap is attached to the frame in any convenient manner, for instance, by means of screws (25), (26), with interposed washers (27), (28).

The length of the strap is greater than the distance separating the two screws in order to 100 allow the intermediate portion of the strap to project outwardly, as shown in Fig. 2, leaving a clearance space (29) between the inner surface of the strap and the outer surface of the frame through which the hand 105 of the player may be inserted. The strap is preferably made of a good grade of leather possessing great flexibility and strength, and the length of its overhanging portion is preferably made adjustable in order to accommodate hands of different size.

When the hand of the player is inserted between the strap and the frame and is made to grip the frame and the segmental projection as shown in Fig. 4, the strap follows the 115 movement of the back of the hand against which it rests, and will remain with its two leg portions downwardly directed, and its intermediate transversal portion along the back of the hand under the frame. In this manner, the two leg portions of the strap act as tension members and positively prevent the frame from being tilted away from the hand if the player should happen to lose or to lessen his grip due to the impact of the ball.

It will be observed that by virtue of this arrangement the hand may practically be locked as it were onto the frame of the device by the tight hold exerted by the strap, 120 while on the other hand, the clearance space 130

normally provided by the strap provides ample room for the free insertion or removal of the hand at any time.

This is due to the fact that when the strap 5 extends outwardly from its points of attachment, the clearance space provided for the insertion of the hand has a width practically equivalent to the length of the legs of the strap while when the strap is forced down- 10 wardly to the position shown in Fig. 4, this clearance space becomes much narrower, being decreased by the distance separating the points of attachment of the strap from the underside of the frame.

15 In order to facilitate the movements of the strap from its hand receiving to its hand retaining position, I prefer to leave the screw connections (25), (26) a little bit loose, permitting washers (27), (28) to revolve about 20 said screws. In this manner the strap becomes attached to the frame by means of pivotal connections which allow free swinging movement of the ends of the strap about the attaching points. This greatly adds to the 25 flexibility of the structure and enables the strap to adapt itself to every curve and irregularity of the player's hand.

The adjustable feature may be had by providing one or both ends of the strap with a 30 plurality of openings such as (30) which may be selectively used for the insertion of screws (25), (26). Another manner of making the strap adjustable is illustrated in Fig. 9, where (31) designates the tambourine frame and (32) designates the strap composed of two members (33) and (34) having their ends overlapping and joined by an 35 adjustable buckle connection (35) of the ordinary type. Although this type of strap 40 may be used at times when light games are played, the type of strap previously described is much to be preferred because it offers a smooth surface of the strap contacting with the hand. The inner surface of the strap 45 shown in Fig. 9 has some sharp edges and projections due to the insertion of the buckle and is apt to hurt if used when heavy games are played.

As stated, the rawhide placed on top of the 50 frame must be heavy and strong in order to be able to stand the impact of the ball. On the other hand, when the game is started, the ball is merely thrown in the air by the batter and is sent into the opponents' field with 55 all the might of which the batter is capable. The impact in this case, however, is much less than during the game when the batter has not only to return the ball as far as he can, but in doing so he has to overcome the 60 tremendous impact with which the ball strikes the tambourine. The range of the batting is dependent upon the strength and skill of the player, but is also to a great extent dependent upon the rebounding qualities of 65 the rawhide covering of the tambourine, so

that in practice it has been found that a tambourine having high rebounding qualities in returning the ball is not very responsive when used for the initial tossing.

Therefore, it has been found that a great 70 improvement will be had if the first delivery of the ball is made by means of a tambourine having a greater than normal resiliency sufficient to respond to the comparatively light impact of a ball falling from but a short 75 height.

A greater resiliency is obtained by using a comparatively light rawhide for the tambourine to be used for the initial tossing, and this is permissible due to the fact that the 80 stress upon the tambourine at that time is much less than the stress experienced when a ball is returned during the course of the game. I have also found that the initial tossing can be performed in a much better way 85 by using a tambourine having an elongated or pear shape, such as shown in Figs. 6, 7 and 8.

The wider portion (36) of this tambourine has about the same diameter across as that of the round tambourine normally used, and its outline extends inwardly to form a narrower gripping end (37), causing the batting or wider portion of the tambourine to remain 90 farther away from the player. This increased distance facilitates the catching of the ball by the player because when the ball is first tossed in the air it is generally tossed somewhat to the right side of the player by the player himself. The increased length of 95 the tambourine at the same time also goes to increase the resiliency of the device, so that all in all a much more responsive tambourine is thus produced, adapted to improve the delivery of the ball when the game starts.

It is important that the tossing tambourine extend laterally rather than forwardly 100 of the player when held in the player's hand if the advantage afforded by its elongated shape is to be fully realized; therefore, I prefer to form the gripping portion of this tambourine somewhat to one side of its central line, that is normally at the right side, if the tambourine is to be used by a right handed 105 player. A firm grip is provided also in this case by an arrangement similar to that previously described comprising a segmental projection (not shown) at the inner side of the frame and a strap such as (38) attached to the outer side of the frame and leaving a 110 clearance space (39) between the inner surface of said strap and the surface of said frame through which the hand of the player may be inserted and retained. The strap is 115 preferably attached as shown in Figs. 6 and 7 with its inner end (40) directly in line with the longitudinal axis of the tambourine and its outer end (41) spaced therefrom to the right at one side of the tambourine, said two 120 ends being secured to the frame as in the 125 130

previous case by means of screws (42)—(43) and loose washers (44)—(45) permitting free swinging movements of the strap about the screws.

5 In Fig. 8, I illustrate the manner of holding the tambourine showing how the lateral end grip enables the player to conveniently hold the tambourine in a laterally extending position ready to catch the ball tossed to his 10 right.

The increased resiliency of this type of tambourine is obtained as stated both by virtue of its elongated shape increasing the "giving" properties of its rawhide top, and by 15 using rawhide of a comparatively light weight, sufficiently strong, however, to stand the impact in batteing the ball into the opponents' territory.

Once the first toss is made, the player quickly 20 changes the tambourine to a normal one, being assisted in this by an assistant in the field, and then the game proceeds as usual until a new game is started.

25 In Fig. 5, I illustrate the possibility of extending the inner segmental projection all around so that instead of having a projection the tambourine becomes formed with a rim (46) extending all around. This type of construction is not generally required, but the 30 same may be adopted at times when an extremely light construction of frame is used and it becomes necessary to re-inforce it. In these cases, however, the weight balancing advantages of the segmental projection previously 35 described will be lost.

From the foregoing it is seen that the invention extends both to a combination of tambourines of different shapes to be used at different stages of the ball game, and to a special 40 construction of the tambourines themselves. The various details of construction of the tambourines may vary to a certain extent from those shown without departing from the inventive idea; for instance, while a rawhide 45 top is to be preferred in all cases for lighter games, an open mesh striking surface such as currently used in tennis rackets could be used if desired, since the gripping feature may be applied in connection with batteing devices used in various games of this character. 50 Therefore I reserve myself the right to carry my invention into practice in all those ways and manners which may enter fairly into the scope of the appended claims.

55 I claim:

1. In a device of the class described, the combination with an open frame and a striking wall extending across the same, of a member inwardly projecting from the lower part 60 of said frame, leaving a clearance space between the upper surface of said member and the lower surface of said wall sufficient to accommodate the end portion of the fingers of a hand gripping said frame.

2. In a device of the class described, the combination with an open frame and a striking wall extending across the same, of a segmental member inwardly projecting from the lower part of said frame, leaving a clearance space between the upper surface of said member and the lower surface of said wall sufficient to accommodate the end portion of the fingers of a hand gripping said frame. 70

3. In a device of the class described the combination with an open frame and a striking wall extending across the same, of a strap having its ends attached to the periphery of said frame normally extending outwardly therefrom leaving a clearance space sufficient to receive the hand of the player inserted 80 therethrough.

4. In a device of the class described the combination with an open frame and a striking wall extending across the same, of a strap having an adjustable length and having its 85 ends attached to the periphery of said frame normally extending outwardly therefrom, leaving a clearance space sufficient to receive the hand of the player inserted therethrough.

5. In a device of the class described the combination with an open frame and a striking wall extending across the same, of a flexible strap having its ends pivotally attached to the periphery of said frame normally extending outwardly therefrom, leaving a clearance space sufficient to receive the hand of the player inserted therethrough. 90

6. In a device of the class described the combination with an open frame and a striking wall extending across the same, of a flexible strap having perforations at each end and a screw adapted to be inserted through one of said perforations at each end in order to secure said strap to said frame at the periphery thereof, so as to normally extend outwardly therefrom forming a loose connection permitting free movements of said strap ends about said screws. 100

7. In a device of the class described the combination with an open frame and a striking wall extending across the same, of a flexible strap having perforations at each end and a screw adapted to be inserted through one of said perforations at each end in order to adjustably secure said strap to said frame at the periphery thereof, so as to normally extend outwardly therefrom forming a loose connection permitting free movements of said strap ends about said screws. 110

8. In a device of the class described the combination with an open frame and a striking wall extending across the same, of a segmental member inwardly projecting from the lower part of said frame leaving a clearance space between the upper surface of said member and the lower surface of said wall sufficient to accommodate the end portion of the fingers of a hand gripping said frame and a 120

hand retaining member adapted to form a clearance space underneath said frame in correspondence of said segmental member sufficient to receive the hand of the player inserted therethrough.

9. In a device of the class described the combination with an open frame and a striking wall extending across the same, of a segmental member inwardly projecting from the lower part of said frame leaving a clearance space between the upper surface of said member and the lower surface of said wall sufficient to accommodate the end portion of the fingers of a hand gripping said frame and a flexible strap having its two ends attached to the outer side of said frame in correspondence of said segmental member, leaving a clearance space between said strap and said frame sufficient to receive the hand of the player inserted therethrough.
10. In a device of the class described the combination with an open frame and a striking wall extending across the same, of a segmental member inwardly projecting from the lower part of said frame leaving a clearance space between the upper surface of said member and the lower surface of said wall sufficient to accommodate the end portion of the fingers of a hand gripping said frame, a flexible strap having perforations at each end and a screw adapted to be inserted through one of said perforations at each end in order to adjustably secure said strap onto the side of said frame in correspondence of said segmental member forming a loose con-

nexion permitting free movements of said strap ends about said screws.

11. A device of the class described, comprising an open frame, a resilient rawhide wall extending across said frame, a segmental member inwardly projecting from the lower part of said frame and leaving a clearance space between the upper surface of said member and the lower surface of said wall sufficient to accommodate the end portion of the fingers of a hand gripping said frame, and a flexible leather strap pivotally attached to the outer side of said frame in correspondence of said segmental member.

12. A device of the class described, comprising a pear shaped open frame, a resilient striking wall extending across said frame, and means for gripping said frame attached to the periphery of said frame, laterally of the axis thereof, at the narrow end of said frame.

13. A device of the class described, comprising a pear shaped open frame, a resilient striking wall extending across said frame, a segmental member inwardly projecting from the lower part of said frame extending to one side of the center portion of the narrow end of said frame, and a flexible leather strap attached to the outer surface of said frame in correspondence of said segmental member, providing a clearance space through which the hand of the player can be inserted to grip said frame.

FERRUCCIO F. CONTOLINI.
